PHOTOGRAPHIC PRINTING APPARATUS.

William E. Merriman and Bradshaw Burnham,
Rochester, N. Y., assignors to Eastman Kodak
Company, Rochester, N. Y., a corporation of
New Jersey

Application December 14, 1939, Serial No. 309,222

4 Claims. (Cl. 88—24)

The present invention relates to photographic apparatus and more particularly to that class of apparatus in which the exposure interval is determined by the rate of change in the charge of an energy storage device, such as a condenser, as controlled by the intensity of the exposing light.

One of the objects of the invention is to provide a time delay apparatus which will give accurate results over a long range of photographic exposures.

A further object of the invention is to provide a photosensitive time delay apparatus which is particularly adapted for the accurate control of exposure intervals in photographic printing.

A number of arrangements are known for controlling a printing interval by varying the charge on a condenser at a rate determined by the activation of a light sensitive cell. However, the range of exposures required in commercial photo finishing is large and simple apparatus, while accurate over a limited range, is not too satisfactory for general use. On the other hand, apparatus designed for accuracy over the required range tends to become complicated and expensive. Some of the arrangements which have been proposed employ in effect several control circuits which are selectively used to obtain the desired results.

Thus, different exposures may be obtained by adjusting the starting charge of the condenser, by terminating the printing interval at a different charge on the condenser, by employing different condensers, by adjusting the characteristics of the charge or discharge path, or in any other well known way, adjusting some factor or factors whereby a predetermined printing intensity will be translated into a different time interval.

In accordance with this invention a light sensitive cell subjected to a known proportion of the printing light regulates the rate of discharge of a condenser which previously had been provided with a predetermined charge, the value of which was selected in accordance with the sensitivity or printing requirements of the paper employed. A vacuum tube relay circuit is employed for obtaining accurate and rapid response and since such a circuit can and should be made very sensitive it is desirable to forestall a repeat exposure by some arrangement for carrying the discharge beyond the critical point at which the exposure is terminated. This is done by maintaining the condenser's discharge path conductive after the termination of the printing interval.

The novel features which are believed to be characteristic of the invention are set forth with particularity in the appended claims. The invention itself, however, both as to its organization and mode of operation, will best be understood by reference to the following description taken in connection with the accompanying drawings in which Figure 1 represents an embodiment of the invention as applied to a photographic printer of the projection type; Figure 2 shows in perspective a schematic arrangement of a circuit similar to that shown in Figure 1; and Figure 3 shows a similar arrangement as modified for use with a direct current source of power.

Referring to the drawings, there is shown diagrammatically a printing apparatus comprising a source of light 10 for illuminating a record 11 to be printed and which is imaged on a sensitive sheet 12 by a suitable lens 13. The starting and stopping of a printing interval is brought about in any well known manner and is here shown as being accomplished by a shutter vane 14 which is biased by a spring 15 to light blocking position and is adapted to be moved to light passing position (shown in broken lines in Figure 2) by a solenoid 16.

For energizing the automatic control arrangement of the invention, a light sensitive cell 17 is positioned to be activated in strict accordance with the intensity of a printing exposure and as shown in the drawings this is accomplished by arranging in the light path a semi-transparent reflector 18 for directing onto the cell 17 a certain proportion of the light transmitted by the record 11 being printed.

With the plug 19 connected to a source of power (the circuit illustrated in Figs. 1 and 2 is designed for operation on 115 volt, 60 cycle alternating current) an energy storage device shown as a condenser C_1 connected in series with a potentiometer network P across the grid and cathode of an electric valve 20 will be charged to the peak value of the A. C. potential at E as shown in Fig. 1. This potential E is of course determined by the setting of the potentiometer P and is preferably variable between about 7 volts and full line voltage.

The photocell 17 is in the discharge path of the condenser C_1 and this path is kept conductive by providing an auxiliary lamp 21 which is made non-actinic by shielding its rays from the sensitive sheet 12 or, preferably, restricting its light to a wave length to which the sensitive material 12 is insensitive but to which the cell 17 is sensitive. The cell 17 is preferably red

sensitive and, accordingly, the lamp 21 may emit red light. Thus, with the discharge path always conducting the rectifying action of the grid of tube 20 will balance the charging and discharging condition which produces a very stable initial D. C. voltage across the condenser C₁. A mercury switch 22, when closed, completes the circuit through the printing lamp 10 and a micro switch 23 which, in operation of the printer, is operated after the switch 22, disconnects the A. C. potential from the grid of tube 20 and connects the cathode of a second tube 24 to the line. The removal of the A. C. potential from the grid of the tube 20 leaves the potential on this grid at a high negative value determined by the charge on the condenser C₁ and thus blocks the passage of plate current in the first tube 20. The plate current of the tube 20 serves to bias the grid of the second tube 24 by reason of the drop across resistance R₂ and, when this plate current stops, the tube 24 becomes conducting and its plate current energizes a coil 25 to close a relay 26 which shunts the red lamp 21.

The shunting of the red lamp 21 throws full line voltage upon the solenoid 18 which removes the shutter vane 14 from the light beam and a printing exposure starts. Upon the starting of this exposure a portion of the light transmitted by the record 11 is directed by the reflector 18 upon the cell 17 and the charge on the condenser C₁ begins to drain off at a rate determined by the intensity of the light transmitted by the record 11. As the condenser C₁ discharges, the potential on the grid of the tube 20 becomes more positive and finally reaches a value at which the tube 20 again becomes conducting and its plate current through the resistance R₂ impresses a biasing potential upon the grid of the second tube 24 to block its plate current, thereby releasing the relay 26 which inserts the red lamp 21 in series with the solenoid 18. This reduced potential on the solenoid 18 is not sufficient to hold against the spring 15 and the vane 14 returns to the position shown in the drawings to discontinue the printing exposure. It will be noted that the red lamp 21 became energized the instant before or simultaneously with the discontinuance of the exposure and thus the cell 17 is kept conducting so as to prevent a repeat exposure which might otherwise be brought about if the charge on the condenser C₁ was not drained below the critical value.

The switches 22 and 23 are preferably arranged to be actuated in the desired sequence upon the movement of a platen 27 to a position at which it holds flat the sensitive material 12 in any well known manner. As shown in Fig. 1, the switch 22 is arranged to be actuated by the platen just prior to its clamping position and the switch 23 is arranged to be actuated by the platen 27 at substantially the instant it reaches its final position. This sequential operation of the switches 22 and 23 insures that the lamp 10 will reach its full brilliancy before a printing exposure is started.

A diode section of the second tube 24 is employed to supply direct current for the plate circuit of the tube 24 and also to supply direct current for the anode of the photocell 17. Thus, although the tube 24 and the cell 17 have returns to the opposite sides of the A. C. line, a single diode supplies direct current for both. It will be clear from the drawing that this is accomplished by the arrangement of the resistance R₃ and the condensers C₃ and C₅, whereby the condensers C₃ and C₅ charge to the same direct current voltage.

The A. C. drop occurs mainly in the resistor R₃.

It is believed to be evident from the above description that the apparatus of the present invention, in addition to providing an accurately timed exposure, possesses many refinements without sacrificing simplicity. For instance, the auxiliary lamp 21 shining on the photocell 17 prevents repeat exposures by, in effect, locking the automatic exposure mechanism in the released condition. This lamp 21 also functions to stabilize the initial charge of the condenser C₁ by establishing equilibrium between the cell current caused by the lamp 21 and the grid current of the tube 20. Due to this arrangement, if the voltage of the supply side of the condenser C₁ is changed in order to print photographic material of different sensitivity, a momentary unbalance of the grid and photocell currents which occurs is quickly restored by the relatively large photocell current. This insures that the proper exposure will be obtained after each sensitivity level change. By arranging the red lamp 21 so that it is visible to the operator, it functions as an indicator of when the exposure has terminated. In the circuit of the lamp 10 there is preferably provided a slide rheostat 28 and a resistance 29 which resistance may be shunted by a switch 30, which switch may be positioned so that it may be convenient for operation by the knee of the operator. With these two means of adjusting the current through the lamp 10, its temperature changes and, of course, a corresponding change takes place in the ratio between the actinic and red light emitted by the lamp 10. Since the photocell 17 is preferably red sensitive, and the sensitive material 12 is generally sensitive in the blue end of the spectrum, a change in the apparent printing level is obtained even though the energy required to discharge the condenser remains constant. Thus, by adjusting the rheostat 28 or shunting the resistance 29, the print density may be altered without adjustment of the automatic control circuit.

In general, if different prints are made at different optical magnifications, it would normally give different photographic results unless the automatic exposure circuit was adjusted. Since any adjustments of the exposure circuit would be difficult to provide in advance, without knowing the focal length of lenses which were to be employed in printing, it is believed preferable to insert in the different lenses a red diaphragm in order to alter the red to actinic light transmission ratio and thereby equalize any number of lenses so that the exposure control system will print properly for all without further adjustment.

It is frequently desirable to print different types of negatives upon different types of printing paper and, accordingly, the potentiometer network P is provided with three separate adjustments so that any one of three switches S, M, or H, which may correspond, respectively, to so called soft, medium, and hard papers, may be closed to alter the exposure control circuit in accordance with the sensitivity of these papers. The arrangement illustrated in Figures 1 and 2 is adapted for operation from alternating current source of supply and if it is desired to operate from direct current, the circuit arrangement of Figure 3 may be employed. In Fig. 3 the parts corresponding to equivalent parts in Figs. 1 and 2 are given corresponding labels and it is believed that inspection of Fig. 3 will enable anyone skilled in the art to build the control arrangement of the invention for operation on direct current.

In one arrangement constructed in accordance

with Fig. 2, the following values of the several impedances were employed: R_1 , 1000 ohms; R_a , 1 megohm; R_3 , 100,000 ohms; and R_4 , 10,000 ohms. The capacities employed were as follows:

	Microfarads
C_1	.005
C_2 , C_4 and C_5	.01
C_3 , C_4 and C_5	4
C_6	.5

It will be understood that these values are given merely as an example of one circuit arrangement and are not to be construed as limiting.

While we have described the preferred embodiments of our invention, it will be obvious that it is not limited to the exact forms illustrated and that many variations may in the particular connections be used without departing from the scope of the invention as set forth in the appended claims.

If manual rather than automatic operation is desired, a switch 31 connected in the main lead from the plug 18 may be moved to contact 32 without breaking its engagement with contact 33. With the switch 31 engaging both contacts 32 and 33 the grid of the second tube 24 is returned to the line through a resistor R_4 (10,000 ohms) in parallel with the resistor R_3 (1 megohm) in the plate circuit of the first tube 20. This resistance is so low that the potential drop due to the plate current of the first tube 20 is too small to bias the tube 24 sufficiently to allow the relay coil 25 to release its armature 26. Therefore, the relay 25 and the solenoid 16 are energized as long as the operator holds down the platen 27.

We claim:

1. In photographic printing apparatus in which the discharge of a condenser determines the printing exposure interval, a light sensitive cell activated in accordance with the printing intensity for governing the discharge of the condenser, means for terminating the exposure when the condenser has been discharged to a predetermined value, and means actuated by the exposure terminating means for discharging the condenser below said predetermined value, whereby surges arising upon the sudden termination of the exposure will not bring about a repeat exposure.

2. In photographic printing apparatus in which the discharge of a condenser through a predetermined range and under the control of a light sensitive cell determines the exposure period, a condenser, an electronic tube having a grid con-

nected directly to one plate of the condenser and having a cathode and an anode, means for impressing an alternating potential between the cathode and grid so that the rectifying action of the grid charges the condenser, a light sensitive cell connected for discharging the condenser in accordance with the conductance of said cell, an auxiliary lamp for illuminating said cell with non-actinic light of sufficient intensity to provide said cell with a conductance such that the discharge current substantially equals the charging current thereby providing a stable and repeatable initial charge for the condenser, means for removing the alternating potential from the grid of said tube, whereby said tube becomes non-conducting, means controlled by the stoppage of current through said tube for starting a printing exposure and extinguishing said auxiliary lamp, means for activating said cell in accordance with the intensity of the printing exposure, thereby discharging the condenser and raising the grid potential at a corresponding rate, means controlled by current through said tube when the grid potential reaches a predetermined value for terminating the printing exposure and energizing said auxiliary lamp, whereby the cell is maintained sufficiently conductive to assure that the potential on the grid does not drop below said predetermined value.

3. In photographic printing apparatus, means for translating the average intensity of the printing light into an inversely corresponding time interval, said means including a condenser, a light sensitive cell for governing the rate of variation of a charge on the condenser and means for terminating the time interval when the charge on the condenser has been varied through a predetermined range, and means operative upon termination of the time interval for continuing the variation of the condenser charge to a value substantially beyond said predetermined range.

4. In apparatus for controlling a photographic exposure, means for regulating the exposure interval comprising a condenser, means for varying the charge on the condenser at a rate strictly proportional to the intensity of the exposure, means responsive to a predetermined variation in the charge on the condenser for terminating the exposure, and means operative upon termination of the exposure for activating said condenser charge varying means, whereby the variation of the charge on the condenser is carried beyond said predetermined variation.
